CIGAR LIGHTER

Filed March 11, 1929

INVENTOR:
Frank E. Williams
BY
Pierre Barnes
ATTORNEY

UNITED STATES PATENT OFFICE

FRANK E. WILLIAMS, OF SEATTLE, WASHINGTON

CIGAR LIGHTER

Application filed March 11, 1929. Serial No. 345,909.

This invention relates to that class of cigar lighters known as pocket lighters.

The object of my invention is the perfecting of devices of this character to render the same more efficient, and convenient in use.

Another object is to provide a lighter of strong, durable and inexpensive construction.

More specific objects and advantages of the invention will appear in the following description.

The invention consists, more especially, in the improved igniting devices and in the manner and means for actuating the same.

The invention further consists in the novel construction, adaptation, and arrangement of parts, and their combination with known parts as will be hereinafter described and claimed.

In the accompanying drawing, illustrating to an enlarged scale of pocket cigar lighter embodying my improvements,—

Figure 1 is a view of the lighter shown partly in side elevation and partly in vertical longitudinal section taken substantially through 1—1 of Fig. 3; Fig. 2 is a view similar to Fig. 1 of the upper portion of the lighter, the section being taken on the line 2—2 of Fig. 3, with the plunger therein broken away and partly shown in side elevation; Fig. 3 is a horizontal section through 3—3 of Fig. 1; and Fig. 4, a transverse vertical section through 4—4 of Fig. 1.

In said drawing, the reference numeral 5 designates the shell or casing of the lighter which serves as a reservoir for the fuel—alcohol or an equivalent—supplied preferably through the medium of a body of a porous material, indicated by 6, to a wick 7 which extends therefrom upwardly through an apertured boss 8 provided in an end of the casing top wall 9.

Provided as a snuffer for said wick and fitting about the reduced upper extremity of the boss 8 is a cap 11 which is rigidly secured to an end of an arm 12 of substantially the shape of an inverted letter U in transverse section.

Adjacent the other end of the arm, the side web elements 13 thereof are apertured to receive a transversely arranged tubular

shaft 14 which is journaled upon a pin 15 (Fig. 4) which is supported by ear elements 16 extending upwardly from the top wall 9 of the casing. As shown in Fig. 4, one end of the pin 15 is screw threaded for engagement with a threaded hole in one of said ear elements, the other end of the pin being slotted to receive a screw driver whereby the pin may be rotated into engaged or disengaged relationship with the casing.

The tube 14 serves as a bushing for a spur gear 17 which is rigid with the cap-carrying arm 12 and in continuous mesh with the spur teeth of a rack bar 18 arranged for reciprocatory motion with a plunger 19 movable in a hollow guide member 20 provided upon the casing top wall 9 at the end remote from the wick. Said guide member is detachably secured to a post element 21 of the casing top by means of a screw 22.

The post 21 is provided with a hole which serves as a guide for a stem 24 extending from the plunger 19. 25 is a spring interposed between said post and the plunger for yieldably retaining the latter in the protruded position in which it is illustrated in Figs. 1, 2 and 3. 26 represents a pyrophoric member positioned in a tube 27 extending through the casing top 9, said pyrophoric member being urged upwardly by means of a spiral spring 28 into contact with an abradant wheel 29 which is mounted for rotation on the bushing 14. Rigid with the wheel 29 is a ratchet wheel 30 engageable by the teeth of a ratchet rack bar 31 which is carried by the plunger when the same is pushed inwardly from the position in which it is shown in Fig. 2.

32 represents a leaf spring acting against said ratchet rack bar to cause the same to be coupled with the wheel 30 to turn the abradant wheel when the plunger is pushed inwardly in opposition to the spring 25, but permitting the ratchet rack bar to be retracted with the plunger without rotating the abradant wheel. The ratchet rack is pivotally connected to the plunger by means of a screw threaded pin 33 which also engages the rack bar 18 whereby the plunger controls the action of both rack bars to impart, through the associated gear 17 and ratchet 34, a reciprocating motion to the plunger.

wheel 30, respectively, movement to the cap 11 from the wick into its dotted line position 11¹ (Fig. 2) and rotation to the abradant wheel 29, when the plunger is manually pushed in one direction to effect the lighting of the wick by means of a stream of sparks from the pyrophoric element.

In such action, the spring 25 is compressed by the plunger and upon being released, the 10 spring asserts itself to retain the plunger to the normal position in which it is illustrated accompanied by both rack bars 18 and 31.

In such return movement of the rack bars, the bar 18 effects the swinging of the cap 11 from its dotted line position to its full line 15 position as shown in Fig. 2, thereby snuffing the light, the rack bar 31 meanwhile traveling below the ratchet wheel 29 without affecting the same, because of the braking of the wheel 20 by the spring pressed pyrophoric element 26 and to the yielding of the spring 32 to permit undulatory movement of the ratchet rack bar with respect to the ratchet teeth of the wheel 30.

25 The peculiar inverted U-shape to the arm 12 enables it to serve as a cover for the gears pertaining to the cap and the pyrophoric wheel. The spring 25 and stem 24 are housed by the plunger and the guide member 20 30 therefor, thus protecting the operating parts of the device and enabling it to be withdrawn from a person's pocket with no liability of catching in his clothing.

By withdrawing the pin 15 the cap 11 and 35 its supporting arm 12 may be readily removed from the device together with the abradant wheel for rotatably adjusting or replacing the same when worn.

The removal of the screw 22 gives access 40 to the plunger from which, in turn, the pin 33 may be removed to release the two rack bars. Thus assembling the various parts above referred to makes the device convenient for the adjustment and replacement of 45 parts.

The wick 7 and the pyrophoric element 26 are adapted to be regulated or replaced as with other lighters hitherto in use.

The operation and advantages of the invention will, it is thought, be understood from 50 the foregoing description.

What I claim, is—

1. A cigar lighter comprising in combination, a casing providing a fuel reservoir, a 55 wick extending from the reservoir through the top of the casing, a spring-pressed pyrophoric member, an abradant wheel mounted adjacent to said spring pressed pyrophoric member in engaging relation with said abradant wheel, a ratchet wheel rigid with said abradant wheel, a wick cap having an arm 60 in transverse section, said arm being pivotally connected with said casing, a gear rigidly with said arm, a manually actuated plunger 65

mounted for reciprocatory movement transversely of the casing, racks for said ratchet and gear wheels respectively carried by said plunger, one of said racks serving to turn the abradant wheel in one rotary direction only, 70 the other rack serving to impart motion to said gear in both rotary directions to cause the wick cap to swing out of and into snuffing relation with the wick, and retractile means acting in opposition to said manual movement to return said plunger into inoperative position.

2. A cigar lighter comprising in combination, a casing providing a fuel reservoir, a wick communicating with said reservoir and projecting through the top of the casing, vertically disposed ears projecting from said top of the casing, a horizontally disposed pin 80 engaging said ears, an abradant wheel rotatively mounted intermediate said ears on said pin and having a ratchet wheel rigid therewith, a spring pressed pyrophoric member in 85 engaging relation with said abradant wheel, a gear wheel mounted on said pin for movement independently of said ratchet, a wick 90 cap having an arm rigidly secured to said gear, a plunger mounted for horizontal movement transversely of the casing, and a pair of racks for said ratchet and gear wheels respectively carried by said plunger, one of 95 said racks serving to turn the ratchet in one rotary direction only, the other of said racks serving to turn the gear in both rotary directions to cause the wick cap to swing out of and into snuffing relation with the wick, said 100 plunger being manually operable to actuate said ratchet and gear wheels in opposition to a spring arranged to return said gear wheel and cap into wick snuffing relation.

3. A cigar lighter comprising in combination, a casing providing a fuel reservoir, a wick communicating with said reservoir and projecting through the top of the casing, a cap arranged for normal snuffing relation over said wick, a gear wheel rigidly secured 105 to an arm of said cap, an abradant wheel, a spring pressed pyrophoric member for engaging relation with said abradant wheel, a ratchet wheel rigid with said abradant 110 wheel, a mounting for said gear, abradant and ratchet wheels, said mounting comprising spaced apart ears projecting above said casing, and a pin projecting through an annulet of one into screw threaded engagement to an aligned annulet of the other, said 115 ratchet and gear wheels having means for actuating the same in one and both rotary directions, respectively, said means comprising a reciprocatory plunger arranged for movement in a horizontal plane transversely 120 of the casing.

4. A cigar lighter comprising in combination, a casing providing a fuel reservoir, a wick communicating with said reservoir and projecting through the top of the casing, a 125

- cap arranged for normal snuffing relation over said wick, a gear wheel rigidly secured to an arm of said cap, an abradant wheel, a spring-pressed pyrophoric member for engaging relation with said abradant wheel, a ratchet wheel rigid with said abradant wheel, a mounting for said gear, abradant, and ratchet wheels, and means including a reciprocatory plunger arranged for movement 5 in a horizontal plane transversely of the casing for actuating said ratchet and gear wheels in one and both rotary directions, respectively.
- 10 5. A cigar lighter comprising in combination, a casing providing a fuel reservoir, a wick communicating with said reservoir and projecting through the top of the casing, a cap arranged for normal snuffing relation over said wick, a gear wheel rigidly secured 15 to an arm of said cap, an abradant wheel, a spring pressed pyrophoric member for engaging relation with said abradant wheel, a ratchet wheel adapted to actuate said abradant wheel in one rotary direction only, 20 a pair of racks for said ratchet and gear wheels, and a plunger connected with said racks, said plunger being manually operable to actuate said ratchet and gear wheels in opposition to a spring arranged to return said 25 30 gear wheel and cap into wick snuffing relation.
6. A cigar lighter comprising in combination, a casing providing a fuel reservoir, a wick extending from the reservoir through 35 the top of said casing, a shaft secured intermediate casing ears projecting above said top, a wick cap having an arm, a gear wheel pivotally mounted on said shaft and rigid with said arm, an abradant wheel mounted upon 40 said shaft and actuated by a ratchet wheel rigid therewith, a pyrophoric member adapted to cooperate with said abradant wheel, a plunger mounted for reciprocatory movement in a horizontal plane transversely of the 45 casing, a pair of racks carried by said plunger, one of said racks being held in engaged relation with said gear wheel for imparting rotary movement in both directions thereto, the other of said racks being pivotally carried 50 by said plunger to engage successive teeth of said ratchet wheel in imparting movement thereto in one direction of rotation, and a spring acting to retract said plunger from its manually impelled operative 55 position, said last named rack being inoperative to said ratchet wheel in the spring impelled retractile movement.

Signed at Seattle, Washington, this 25th
day of February, 1929.
FRANK E. WILLIAMS.
